UNITED STATES PATENT OFFICE.

TIMOTHY J. WHOLEY, OF PHILADELPHIA, PENNSYLVANIA.

WHEEL-FLANGE LUBRICATOR.

1,094,955.

Specification of Letters Patent. Patented Apr. 28, 1914.

Application filed May 22, 1913. Serial No. 769,160.

To all whom it may concern:

Be it known that I, TIMOTHY J. WHOLEY, a citizen of the United States, residing in the city and county of Philadelphia, State 5 of Pennsylvania, have invented a new and useful Wheel-Flange Lubricator, of which the following is a specification.

My invention consists of a wheel-flange lubricator of the type disclosed in Letters 10 Patent, No. 990,034, dated April 18, 1911, and No. 1,039,650, dated September 24, 1912, both granted to Philip Conniff, and particularly of improved means for retaining the cap closing the rear end of the lubricant 15 box or holder.

It further consists of improved means for holding the rear end of the feeding spring.

It further consists of other novel features of construction, all as will be hereinafter 20 fully set forth.

The annexed drawings and the following description set forth in detail one mechanical form embodying the invention, such detail construction being but one of various 25 mechanical forms in which the principle of the invention may be used.

In said annexed drawings—Figure 1 represents a longitudinal section of my improved lubricator. Fig. 2 represents a rear 30 end view of the holder and cap with the chain removed. Fig. 3 represents a rear end view of the holder with the cap removed. Fig. 4 represents a face view of the cap. Fig. 5 represents an axial section of the cap. 35 Similar numerals of reference indicate corresponding parts in the figures.

Referring to the drawings, the reference numeral 1 indicates the barrel of the lubricant holder, having the stem, 2, by means 40 of which the device is supported in proximity to the wheel, as disclosed in the above-named Letters Patent. Said barrel is preferably rectangular in cross-section, such being usually the shape of the bar or stick of lubricant used in these devices. At the rear end of the barrel is an enlarged cylindrical chamber, 3, forming a shoulder, 4, and having a number of inwardly projecting flanges or lips, 5, upon its rear edge,—in the present 45 instance, four. A cap, 6, fits in said chamber and has a peripheral flange which is cut away to form notches, 7, adapted to register with and slip inward over the lips upon the edge of the chamber. The outer 50 faces of the tongues, 8, formed by notching the flange are formed with recesses, 9, cor-

responding in size and shape to the lips, and adapted to register with and engage such lips when the cap is inserted into the open end of the chamber and partly rotated. A 60 coiled spring, 10, fits in the cylindrical chamber and bears against the shoulder of the same and against the inner face of the flange of the cap, thus holding the recesses and lips in engagement when seated. A 65 polygonal boss, 11, is formed upon the outer face of the cap, or other similar projection is provided by means of which the cap may be manipulated. A projecting socket, 12, is formed upon the inner side of the cap. A 70 follower, 13, fits to slide within the bore of the barrel, and has a recess, 14, into which the tenoned end of the stick of lubricant, 15, fits. A coiled spring, 16, bears against said follower and has its rear end confined in the 75 socket of the cap. A chain, 17, or similar flexible connection has one end secured to the follower and passes through an opening, 18, in the cap and is secured with its other end to the latter. A ring, 19, having a pin, 80 20, is provided for drawing the chain rearward and for adjusting it and the follower, similar to the ring and pin disclosed in the Conniff Patent, No. 1,039,650, above referred to.

In lubricators of this type, as heretofore made, cams or set-screws have generally been employed to secure the cap to the end of the barrel, and, as the lubricator is supported from the truck of a car or locomotive, it is subjected to constant vibrations and jolts while in use. Such fastening means have rapidly become loosened with the result that the cap falls out, carrying with it the chain, follower and stick of lubricant. The spring in the present device will hold the lips upon the edges of the chamber in engagement with the recesses in the tongues of the cap, taking up the vibrations and movements from shock. The cap 100 can be removed by pushing it inward and giving it a slight turn,—in the illustrated form a one-eighth turn,—when the chain spring and follower can be removed and a new stick of lubricant inserted, and securing of the cap is equally simple. The tension of the follower-spring will, when the lubricant stick bears against the wheel, assist in holding the cap against the lips upon the edge of the chamber and thus the 105 tendency of said spring, in the present device, is to keep the locking means in en-

gagement and the cap seated, while in former devices this tendency has been the reverse. The inter-engaging and alternately interrupted flange-joint and interlocking 5 projections and depressions with the yielding means for holding the parts in engagement accomplish the present advantage.

Other modes of applying the principle of my invention may be employed for the 10 mode herein explained. Change may therefore be made as regards the mechanism thus disclosed, provided the principles of construction set forth, respectively, in the following claims are employed.

Having thus described my invention, what 15 I claim as new and desire to secure by Letters Patent, is:—

1. In a device of the character stated, a lubricant-holder comprising a barrel having 20 a passage therethrough, a follower therein adapted to receive a stick of lubricant, a chamber at the rear end of said barrel having a shoulder formed at the junction of said chamber and passage, lips projecting 25 inwardly from said chamber, a cap fitting in said chamber, interlocking devices common to said cap and lips, a spring in said chamber intermediate said shoulder and said interlocking devices, and a spring intermediate 30 said follower and said cap.

2. In a device of the character stated, a lubricant-holder, a cap for closing the end 35 of the same, said elements formed with in-

ter-engaging and alternately interrupted flange-joint elements having their opposed 35 engaging faces formed with corresponding projections and depressions, and yielding means bearing against said holder and cap to hold such joint-elements in engagement.

3. In a device of the character stated, a 40 lubricant-holder having a chamber at its rear end provided with inwardly-projecting spaced lips, a cap fitting in said chamber and formed with notches corresponding to said lips and with tongues between such 45 notches having recesses in their outer faces corresponding to said lips, and a spring seated in said chamber and bearing against said cap.

4. In a device of the character stated, a 50 lubricant-holding barrel, a chamber at the rear end of said barrel provided with inwardly-projecting spaced lips, a follower in said barrel, a cap fitting in said chamber and formed with peripheral notches corresponding to said lips and with tongues between such 55 notches having recesses in their outer faces corresponding to said lips, a spring seated in said chamber and bearing against said cap, and a spring interposed 60 between said follower and cap.

TIMOTHY J. WHOLEY.
